DESIGN FOR AN ASH TRAY

George McStay Jackson, Lake Forest, Ill., assignor to Design Fabricators, Inc., Chicago, Ill., a corporation of Illinois

Application March 29, 1947, Serial No. 138,040

Term of patent 3½ years

(Cl. D85—2)

To all whom it may concern:

Be it known that I, George McStay Jackson, a citizen of the United States, residing at Lake Forest, in the county of Lake and State of Illinois, have invented a new, original, and ornamental Design for an Ash Tray, of which the following is a specification, reference being had to the accompanying drawing, forming a part thereof.

In the drawing—

I claim:

The ornamental design for an ash tray, substantially as shown.

GEORGE McSTAY JACKSON.
